Continuation of application Serial No. 127,690,
 November 16, 1949. This application January
 8, 1953, Serial No. 330,324

12 Claims. (Cl. 206—46)

1

This application is a continuation of Serial No. 127,690, filed November 16, 1949, and now abandoned.

This invention relates to shipping and storage containers and particularly to such containers for jet-type engines.

Jet engines of the type presently used in aircraft, particularly military aircraft, have a relatively short useful life between overhauls and it is the practice to provide several spare engines for each aircraft equipped with this class of propulsion device.

The problem of storing and shipping these engines has presented difficulties because of their bulky construction and because it is necessary to seal the storage container against the entrance of air and moisture to prevent corrosion.

It is therefore the primary object of my invention to provide an improved storage and shipping container for jet engines which will adequately protect an engine stored therein against physical damage and from damage due to exposure to the elements.

Further objects are to provide a container of the aforesaid type which is easily manufactured, readily adapted for handling by standard freight handling equipment, strong enough to withstand the hazards of shipping and handling, adapted for stacking in stacks of three or more, and which is provided with means for easily removing and replacing the engine.

Other objects and advantages will be apparent from the following specification which, in connection with the accompanying drawings, describes preferred embodiments of the invention.

In the drawings,

Fig. 1 is a side elevation, with parts broken away to show sectional details, of one form of my invention;

Fig. 2 is a section along line 2—2 of Fig. 1;

Fig. 3 is a front elevation of the container of Fig. 1 with certain parts broken away to show details thereof;

Fig. 4 is a section along line 4—4 of Fig. 1;

Fig. 5 is a section along line 5—5 of Fig. 1;

Fig. 6 is a side elevation of a modified container;

Fig. 7 is a side elevation of another modification of the invention;

Fig. 8 is an end elevation of the Fig. 7 container with parts broken away to show details; and

Fig. 9 is a sectional view along line 9—9 of Fig. 7.

Referring to Figs. 1 to 5 inclusive, it may be seen that my improved jet engine container com-

2

prises a cylindrical tank-like structure 10 having a removable front portion 11. The construction is preferably of steel plates welded or riveted together and is of relatively heavy section in the order of one-eighth inch in thickness. The cover portion 11 and the main portion 10 are respectively provided with mating flanges 12 and 13 (see detail Fig. 5) which are adapted to abut one another for securing the two portions together. A resilient gasket 15 is provided for sealing the joint between the flanges against entry of air and moisture and the fastening bolts 14 are adapted to be tightened to provide metal to metal contact of the flanges.

The flanges 12 and 13 are arranged at an oblique angle (approximately 45° has been found satisfactory) with respect to the horizontal and vertical axes of the container and at such a position lengthwise thereof that when the cover 11 is removed the opening thereby provided extends a considerable distance rearwardly at the top and sides and diminishes toward the bottom such that substantially all of the bottom length remains for support and protection of the engine.

Reinforcing metal straps 16 having folding hook-eyes pivotally mounted thereto are provided for hoisting the container as a unit and for removing the cover portion.

The cylindrical portion of the container is supported in a rectangular cradle 14', the sides 15' thereof extending about halfway upwardly of each side of the tank and being shorter than the tank (see Fig. 1). The sides are cut off at their forward ends on an oblique line corresponding with the flange 13. Wooden skid rails 18 are bolted or otherwise securely fastened to feet provided at each corner of the cradle. Pillow blocks 19 incorporating rubber shock absorber pads 20 are disposed between the rails and feet.

Near each end of the container in vertical alignment with the ends of the cradle side portions, and at the central portion of the container, rectangular saddles 11' are provided. These saddles are welded to the cylinder over the reinforcing straps 16 and are provided with ledges 21 for receiving the skid rails of a second container. By this means it is possible to stack containers several tiers high and thus conserve space on shipboard or loading dock.

The jet engine itself is shown in outline by the broken line 22 in Figs. 1 and 3. This type of engine is usually provided with trunnion members 23 for mounting in the airplane, and in some models a link 24 is carried at one end for securing the engine in the airplane against rock-

ing. I have utilized these standard engine mountings for suspending the engine in the container such that the engine is firmly supported therein and insulated against shocks, yet easily placed in the container and removed therefrom.

On each side of the container, I have provided a "blister" 25 which houses the supporting means for the engine. This supporting means, shown in section in Fig. 4, comprises a pair of rails 26 resiliently mounted at each side of the container in such position that the jet engine may be supported in the container by means of the trunnion members 23.

In the embodiment illustrated in Figs. 1 to 5, inclusive, the rails 26 are formed of relatively heavy cast metal and are yieldably mounted on the longitudinally disposed members 27 by the cushion members 28. The longitudinal members 27 are welded or otherwise securely affixed to the cylindrical side walls 10 of the container and to the wall of the blister. The cushion members 28 consist of a pair of rubber "doughnuts" 29 bonded at their inner peripheral surfaces to a hollow member 30. The upper doughnut carries an annular plate 31 disposed axially thereof and bonded to the rubber approximately centrally of the axial length thereof. This plate extends circumferentially of the cushion member and the circumferentially extending portion is adapted to be received in slots 32 formed in the downwardly extending portion of the rail 26. A similar plate 33 carried by the lower doughnut 29 is received in slots 34 formed in the angle members 35 which are carried by the side members 27. Safety plates 36 are carried by the hollow members 30 for preventing complete separation of the doughnuts 29 and the member 30 in the event the bond between the rubber and metal should be broken in use.

In the embodiment being described, three cushion members 28 are used for supporting each of the elongated rails 26. Obviously, a more or less number of cushion members may be used if desired.

The rails 26 are each provided with a tapered slot or way 37 for receiving tapered rollers 38 carried by the engine trunnions 23. The rollers 38 are rotatably secured on stub axles 39 which stub axles are mounted in a trunnion bracket 40. The brackets 40 each carry a hanger member 41 which extends forwardly and downwardly of the container as shown in Figs. 1 and 3. The two hangers 41 meet at a point aligned with the link 24 and have a socket formed therein for receiving the ball on the end of said link. Suitable bolts 42 are provided for securing the ball end of the link in the socket.

The procedure for mounting an engine in the container just described is as follows:

The special brackets 40 are bolted to the engine over the regular engine trunnion brackets and the rollers 38 mounted thereon. The engine is then picked up by a crane or other hoist and lowered into the tank through the opening provided by removing the cover 11. The rollers 38 are guided into the slots 37 at the forward ends of the rails 26 and the engine is urged rearwardly until the hangers 41 can be fastened about the ball at the bottom of link 24.

The cover 11 may then be lifted by means of the eye 17 and placed on the main body of the container whereupon the bolts 14 are tightened until the flanges 12 and 13 meet, compressing the gasket 15 to make an air-tight seal. The container is then in condition for handling, ship-

ping and stacking without danger of damaging the jet motor contained therein. The motor is easily removed from the tank by reversing the steps just described.

Fig. 6 illustrates a modified form of my improved container wherein the rails 26 are elongated and are supported at their front ends by a pair of cushion members 28 and at their rear ends by a single cushion member. This form of container is adapted for use with jet motors not provided with stabilizing links at one end thereof. Two sets of rollers are used, each set being carried by brackets 40 bolted to the motor at longitudinally spaced points on each side thereof.

Figs. 7 to 9 inclusive, illustrate a further modification of the invention. In this form, the jet motor supporting rails 50 extend substantially the entire length of the tank and protrude outwardly thereof when the cover is removed, as shown in Fig. 7.

The rails are each suspended in the tank by means of six cushion members 51. The latter are positioned at each side of the tank, three above and three below the rail at each side as shown. The cushion members are mounted on annular plates 52 which are welded to the interior of the blisters 53, the latter in turn being welded to the tank wall around the opening provided for accommodation of the cushion mounting.

The rails 50 are suspended from the cushion members by means of the channel-shaped hangers 54. The hangers are provided with a groove for receiving one of the plates carried by one of the rubber biscuits of the cushion member in a manner similar to the mounting shown in Fig. 4, and the other end of the hanger is bolted to the rail as indicated at 55. It is apparent then that the rails 50 are yieldably mounted in the tank such that they have limited universal movement yet give firm support to the engine carried thereon. If desired, a greater number of cushion members may be utilized, depending upon the weight and size of the jet engine to be accommodated.

In this modification of the invention, the jet engine is supported at two points on each side. In Fig. 8, the line 56 represents one side of an engine. Brackets 57, such as that shown in section in the figure, are bolted or otherwise secured to the engine at spaced points on each side thereof. Each of these brackets 57 has a rounded socket adapted to raise the rounded end 58 of the stub axle which carried the roller 59. Rollers 59 are of the same cone shape as those used in the modifications previously described and are adapted to run in the undercut grooves provided in the rails 50 as illustrated.

As previously mentioned, the rails 50 extend outwardly of the container body 60 when the cover 61 is removed. After an engine is mounted in the container, lock bars 62 (shown in dotted lines in Figs. 7 and 9) are inserted in the grooves in each of the rails for locking the engine in place. The lock bars are provided with a bifurcated end for engaging the stub axle adjacent the ball portion 58 thereof. The grooves in the rails extend only part way of the length thereof thereby limiting rearward travel of the rollers 59.

To prevent displacement of the lock bars 62 and brace the forward ends of the rails 50 against each other, a transverse bar 63 is disposed between the rails and connected thereto by means

of pins 64 in the manner of the familiar hinge joint.

The form of container presently being described is provided near its ends with "hoops" 65 and 66. These hoops are fabricated of steel plates and are rounded in shape at the top and sides such that the container will be protected against severe shock if accidentally rolled over and may be easily rolled back on its skid rails if overturned. Eyes 67 for the reception of a crane hook are provided at the top of the hoops and a reinforcing bar 68 is welded in the hoop above each eye to distribute the stress during lifting.

The forward hoop 66 is separable at points adjacent the flanges of the cover to facilitate quick removal of the cover. The top portion of the hoop 66 carries a pair of studs 69 adapted to be received in the apertures 70 at each side of the lower portion.

It may thus be seen that I have provided an improved container for jet motors which provides full and adequate protection for the motor during storage and shipping. It is frequently necessary for the military services to store spare motors for months, even years, and to transport them to remote bases, sometimes with primitive forms of transport. In many instances facilities for removing the motors from the containers is not all that could be desired and in time of military emergency it is frequently necessary to change aircraft motors in a few moments.

My container is adapted to meet all conditions likely to be encountered in storing, handling, transporting, and in the field; and while I have illustrated and described only a few of the preferred forms of my invention, it is to be understood that other forms are contemplated and I do not intend to limit my invention to the precise forms shown, but only as set forth in the claims appended below.

I claim:

1. A storage and shipping container for engines comprising a normally horizontally disposed cylindrical body separable along a plane disposed obliquely to the axis thereof and extending from one end of the container at the bottom thereof to a point at the top of the container intermediate the ends into a main portion and a cover portion, mating flanges carried by said portions, a cradle for supporting said body, said cradle having side walls extending upwardly of said body to a line substantially midway of the height thereof and terminating at the cover end at the plane of said flanges.

2. A shipping and storage container for engines comprising a normally horizontally disposed cylindrical body separable into a main portion and a cover portion, a pair of rails disposed axially inside said main body portion at each side thereof for mounting an engine, means mounting said rails including yieldable members permitting limited movement of said rails in all directions, said mounting means comprising a support rigidly mounted in said body portion at each side and above the bottom thereof, a plurality of cushion members secured to said support in longitudinally spaced relation and extending vertically upwardly thereof and means for securing the rail to the cushion members upwardly of said support.

3. In a storage and shipping container for an engine of the type provided with trunnion supports at each side thereof and a stabilizing link at one end thereof, rails disposed longitudinally of said container, means for mounting said en-

gine in the container on said rails permitting longitudinal movement of the engine for loading and unloading, a pair of hanger members carried by said rails and extending downwardly and longitudinally thereof, and means in said hanger members for securing them to each other and to said stabilizing link.

4. A storage and shipping container for engines comprising a cylindrical body adapted to be opened for loading and unloading an engine, a substantially rectangular cradle for supporting said cylindrical body, skid rails disposed longitudinally at the bottom of said cradle, saddle members fixed to said body at each end thereof, said saddle members having step portions formed thereon at the top thereof for receiving said skid rails thereby permitting several containers to be stacked vertically.

5. In a storage and shipping container for engines, a pair of rails yieldably mounted in said container and extending longitudinally thereof, an undercut groove in each of said rails, a plurality of cone shaped rollers adapted to run in said grooves, each of said rollers being mounted on a stub axle terminating in a ball, and mounting brackets having sockets for receiving said balls, said brackets being adapted for mounting on said engine at spaced points whereby the engine may be suspended on said rails for restricted universal movement.

6. A storage and shipping container for engines comprising a cylindrical body adapted to be opened for loading and unloading purposes, skid rails secured to the body at the bottom thereof, yieldable blocks disposed between the rails and body for absorbing shocks that might otherwise be transmitted to said body, protrusions on the sides of said body for housing engine mounting means contained therein, and hoop members fixed to said body near each end thereof, said hoop members being rounded at their sides and top such that said container may be overturned without damage.

7. A container in accordance with claim 6 wherein said hoop members are provided with stepped portions at their upper portions for receiving the skid rails of another container thereby permitting several containers to be vertically stacked.

8. A storage and shipping container for jet engines comprising a cylindrical tank-like body, means for separating said body along a plane oblique to the axis thereof into a main portion and a cover portion, a pair of rails mounted in said body and extending axially at each side thereof, said rails extending outwardly of said main portion when the cover portion is removed, means for yieldably suspending said rails in said body such that they may have restricted universal movement, said suspension means including resilient members disposed at spaced points axially of the container and above and below said rails.

9. A container according to claim 8 wherein rollers are provided for running in said rails and means is provided for mounting said rollers on an engine for universal movement relatively thereto.

10. A shipping and storage container for engines comprising a normally horizontally disposed cylindrical body separable into a main portion and a cover portion, a pair of rails disposed axially inside said main body portion at each side thereof for mounting an engine, means mounting said rails including yieldable members per-

mitting limited movement of said rails in all directions, said mounting means comprising a support rigidly mounted in said body portion at each side and above the bottom thereof, a cushion member secured to said support and extending vertically upwardly thereof, and means for securing the rail to the cushion member upwardly of said support.

11. A shipping container for a jet engine comprising, a first shell and a second shell each having end walls and adapted to meet along a plane to form a closed cylindrical container, means along the confronting edges of said shells to connect the first shell to the second shell, means attached to the first shell to serve as container-supporting and floor-contacting elements, bracket means on opposite sides of said first shell and rigidly attached thereto on the inside surface, resilient supporting elements mounted on said brackets, a pair of engine bearing beams at opposite sides of said first shell and supported by said resilient supporting elements, and trun-

nion supporting devices on each of said beams and adapted to removably retain laterally projecting trunnions fixed on said jet engine at opposite sides thereof.

5 12. A shipping container for a jet engine comprising, a first shell and a second shell adapted to meet along their peripheral edges to form a closed container, means along the confronting edges of said shells to connect the first shell to the second shell, a plurality of bracket means on opposite sides of said first shell and rigidly attached thereto on the inside surface, resilient supporting elements mounted on said brackets and including rubber cushioning blocks, a pair of similar parallel engine bearing beams at opposite sides of said first shell and supported by said resilient supporting elements, and engine supporting brackets on each of said beams and adapted to removably retain projecting elements fixed on said engine at opposite sides thereof.
